GROUND-EFFECT VEHICLE

Nickolaus E. Leggett, 44 W. 77th St., New York, N.Y.
Filed Aug. 18, 1964, Ser. No. 390,346
5 Claims. (Cl. 180—7)

This invention relates to ground-effect vehicles and more particularly to vehicles which are supported above the ground by means of a low pressure free air cushion generated by a fan mounted in the vehicle on an axis perpendicular to the ground.

Propulsion and directional control of ground-effect machines are normally provided by mechanism outside the confines of the machine itself while suspension of the vehicle is afforded by components within the vehicle which cause a directed air flow downwardly therethrough to form a cushion or pad beneath the vehicle which supports the latter in frictionless, spaced relation with the ground.

According to the present invention both the means for creating the downward draft and the means for affording propulsion and directional control are disposed within the vehicle. In general this is achieved by stationing a device in the air stream which will as a consequence of its own shape or motion create a differential pressure effect on two sides thereof sufficient to cause motion and by either orienting or shielding the device as by deflectors produce the desired steering torque.

One object of the invention is to provide a new and improved ground-effect machine.

Another object of the device is to provide a ground-effect machine having internal component to establish its propulsion and steering forces.

A further object of the invention is to provide a machine of this character with a stationary air foil disposed in the air stream and internal means to provide steering control.

Other objects and advantages of the invention may be appreciated on reading the following description of one embodiment of the invention which is taken in conjunction with the accompanying drawings, in which:

FIGURE 1 is an illustration of one embodiment of the invention;

FIGURE 2 is a section taken on line 2—2 of FIGURE 1;

FIGURE 3 is a section taken on line 3—3 of FIGURE 1;

FIGURE 4 is a section taken on line 4—4 of FIGURE 1;

FIGURE 5 shows a modified embodiment of the invention;

FIGURE 6 is a section taken on the line 6—6 of FIGURE 5;

FIGURE 7 is a section taken on the line 7—7 of FIGURE 5;

FIGURE 8 is a section taken on line 8—8 of FIGURE 9 showing another modified version of the ground effect vehicle which is a torque controlled device;

FIGURE 9 is a section taken on the line 9—9 of FIGURE 8.

Referring to FIGURE 1 of the drawings, there is illustrated the usual ground effect machine 10 having a vertical cylindrical tunnel portion 12 and depending nozzle section 14 which contain a peripheral annulus 16 to jet the air into the space defined by the ground and the base of the vehicle.

In the top portion 12 is provided the usual fan or propeller 18 and an air foil 20 structurally mounted on a rotatable ring 21 within the machine. The ring is supported in annular tracks 22 and 23 and operated from the cabin 24 by means of pinion 25 which is in engage-

2

ment with ring gear 26 affixed to the inner surface of the ring 21. The foil 20 is similar in shape to an airplane wing with a flat forward surface 27 and convex surface 28. Also mounted on the ring above the air foil is a deflector 30 secured to pinion 32 engaging ring gear 34 slidably supported on the ring 21 and turned by pinion 36. The deflector serves as an air flow spoiler above the air foil to control the flow in the region of the foil and hence to control the propulsion force generated by the foil in accordance with the set position of the deflector. It can be seen that by orienting the air foil in the desired direction of travel the resultant force of propulsion acting on the foil will afford steering control. Clutch 37 may be used to declutch pinion 25 when deflector 30 is being positioned. The force may be modulated by the single deflector 30 which may be turned to a horizontal position to eliminate it entirely when no propulsion is desired. Supplemental steering may be supplied by rudder 38 acted on by air flow through the scoop 40.

As shown in FIGURES 8 and 9, two deflectors 42 and 44 are mounted upon concentric shafts 46 and 48 respectively above stationary air foil 20 which is structurally attached directly to the vehicle. The deflectors are independently controlled by rack and pinion drives 52 and 54. The two deflectors extend together the entire width of the foil and are used to control the velocity of flow past each half of the foil, as desired, to effect a torque control on the foil by operating one or both deflectors. In addition turning torque will be afforded as a consequence of the reactive forces of the air flow on the deflectors themselves.

As shown in FIGURES 5, 6 and 7 the air foil 20 is disposed within an air duct 56 at the top of which are stationed two pairs of opposing, deflectors 58, 60, and 62, 64, the deflectors 60 and 64 and the deflectors 58 and 62 being mounted on coaxial shafts and extending the entire width of the foil 20. Each pair of opposing deflectors has its own rack and pinion control operable independently of the other pair. Pinions 66 and 68 carried by opposing deflectors 58 and 60, respectively, engage rack 70 on opposite faces while pinions 72 and 74 supported by opposing deflectors 62 and 64, respectively, engage rack 76 on their opposite faces. The deflectors can be employed to shut off the air flow past the foil and effectively prevent any propulsive force from developing. The deflectors can also be used to afford turning torque as desired as well as to control the amount of propulsion force on the foil.

Various modifications of the invention may be effected by persons skilled in the art without departing from the scope and principle of the invention as defined in the appended claims.

I claim:

1. In a ground-effect vehicle, means for producing a suspensory air flow therewithin and an air foil disposed within the vehicle and in the path of said flow, said air foil having opposing surfaces of different contours, the forward contoured surface having a greater convexity than its opposing surface, said forward contoured surface being at least in part disposed across the air stream, whereby propulsion forces due to Bernoulli effect are established within the vehicle, at least one air flow deflector stationed in the air flow above the air foil and rotatably mounted to control the flow about said foil.

2. In a ground-effect vehicle as defined in claim 1 in which there is an air duct, said foil being disposed in said duct and said deflector being arranged to close off the flow within said duct.

3. In a ground-effect vehicle as defined in claim 2 in which there is an air duct, said foil being disposed in said duct, at least two pairs of opposing deflectors in said vehicle arranged to control the air flow past said foil,

each pair of deflectors being operatively independent of the other.

4. In a ground-effect vehicle as defined in claim 1 in which there is a plurality of rotatable deflectors together extending the entire width of said air foil, said deflectors being operatively independent.

5. In a ground-effect vehicle, means for producing a suspensory air flow therewithin and an air foil disposed within the vehicle and in the path of said flow, said air foil having opposing surfaces of different contours, the forward contoured surface having a greater convexity than its opposing surface, said forward contoured surface being at least in part disposed across the air stream, whereby propulsion forces due to Bernoulli effect are established

within the vehicle at least one air flow deflector stationed in the air flow above the air foil and rotatably mounted to control the flow about said foil, a rotatable ring stationed in said vehicle said non-rotative air foil and deflector being mounted in said ring and oriented thereby for directing the resultant force of propulsion.
